Application December 10, 1949, Serial No. 132,374

30 Claims. (Cl. 26—18.5)

1

This invention relates to the treatment of tubular textile fabrics and particularly to a novel method of preshrinking and setting such fabrics so that garments made therefrom will not be subject to further substantial shrinkage as the result of laundering.

It has been the practice heretofore to treat tubular textile fabrics to a steaming and calendering operation to finish the fabric prior to cutting into garments. In the standard procedure, the tubular fabric is advanced over a spreader which subjects the fabric to lateral and longitudinal tension as it advances, the longitudinal tension being maintained to the point where the fabric is gripped by the calender rolls. After passing the calender rolls where it is subjected to pressure and sometimes heat, the fabric is rolled or folded and delivered to the cutting tables. Because of the longitudinal tension which is maintained throughout the steam treatment, no shrinkage is permitted, and consequently the finished fabric is subject to shrinkage when laundered.

It is the object of the present invention to provide a method of and apparatus for treating tubular textile fabric whereby the fabric is longitudinally compressed before, during or after steaming and is not therefore subject to substantial additional shrinkage as a result of laundering, an object which has long been considered desirable but heretofore has not been obtainable in the treatment of tubular textile fabrics.

Another object of the invention is the provision of a method of and apparatus for setting the stitches of a tubular textile material in their natural form and contour and free of internal stress, with a reduction in the inherent residual shrinkage so that garments made therefrom are not subject to modification by substantial shrinkage.

Another object of the invention is to permit calendering or finishing the fabric by the application of rolling pressure thereto without interfering with the desired shrinkage.

A further object of the invention is the provision of a method of and apparatus for treating tubular textile fabrics which do not depend upon the previous condition or treatment of the fabric, being universally applicable to the many varieties of such fabrics which appear in commerce.

Other objects and advantages of the invention will be apparent as it is better understood by reference to the following specification and the accompanying drawing, in which

Fig. 1 is an elevation of the feeding end of the machine;

2

Fig. 2 is a plan view of the structure shown in Fig. 1;

Fig. 3 is an elevation of the delivery end of the machine;

Fig. 4 is a plan view of one side of the propeller;

Fig. 5 is a section on the line 5—5 of Fig. 2;

Fig. 6 is a section on the line 6—6 of Fig. 2;

Fig. 7 is an elevation partially in section of 10 the mechanism for controlling the pressure of the finishing rolls;

Fig. 8 is a side view of one of the propeller pulleys.

The present invention depends upon the application of an aqueous medium such as steam or water as a finely divided spray to the fabric while the latter is in relaxed condition with respect to its longitudinal dimension, the steam, for example, being applied in a particular manner so that all parts of the fabric are uniformly treated and subjected to identical conditions as it advances. After steaming, the fabric may be subjected to a blast of air, cold or heated, and applied in a manner and in sufficient quantity 15 to remove the moisture supplied by the steam. However, we have found that excellent results are obtainable when the air is omitted and its use is therefore optional. As during the steaming treatment, the treatment with air if used 20 must be carried out while the fabric is relaxed longitudinally, no longitudinal tension being permitted at any point in the fabric during or after steaming.

Calender or finishing rolls may follow or replace the air drying of the fabric, provided that such rolls are so operated as to avoid longitudinal tension in the fabric. Thereafter, the fabric is conveyed, still without longitudinal tension, 25 preferably to a folding device which delivers the fabric in layers.

The initial condition is the feeding of the fabric in a relaxed condition. The fabric is delivered by any suitable mechanism from the pile or roll, so that there is no longitudinal tension in the 30 fabric, to a propeller. The propeller is a frame 45 operating within the tubular fabric, which spreads it laterally to the desired width in a flattened form. The propeller is provided with endless belts on each side in two sets. The fabric is spread to any desired width on the first set 45 which operates at a predetermined speed higher than that of the second set. Thus, as the fabric is advanced, it is overfed as it engages the second set of belts which, because of the lower speed, 50 causes the fabric to compress, with the result that 55 causes the fabric to compress, with the result that ruffles appear in the fabric, thus ensuring that all longitudinal tension is completely relieved.

There are no frictional spreader parts engaging the advancing fabric. There is rolling and driving contact throughout. As the cloth passes on to the propeller, it is in contact with the entry rolls, then passing to the driven belts which both spread and drive the cloth. An important feature of this propeller is the uniformity of drive and speed of each set of belts, so that both edges of the fabric are delivered uniformly both over the primary and secondary sets of belts. The grooves of the radius rolls which drive the belts are knurled, and this knurl is impressed in the elastic rubber covering of the belts which therefore gives positive drive. The rubber belt itself consists of an internal core which is non-elastic and an outside rubber covering which is of elastic rubber. This results in a constant outside speed of the belts on the propeller with positive grip. No slippage, frictional or otherwise, is thus possible.

When the fabric is free from longitudinal tension as evidenced by the ripples, steam is applied in the form of a jet or jets extending transversely of the fabric from both above and below the fabric, the upper and lower jets being opposed so that the pressure of the jets is balanced and no pressure is exerted to distend the fabric. A suitable device for applying the steam is disclosed in the co-pending application Ser. No. 118,086 filed September 27, 1949, and the details thereof form no part of the present invention. Other steaming means may be utilized, although the steam chests as disclosed in said application are most effective for the purpose, since distortion of the fabric due to the pressure of the steam is avoided, the pressure of the opposed jets being neutralized. Whatever steaming means are used may be applied to the advancing fabric while it is passing over either set of propeller belts or both; that is to say, the steam may be applied at any point between the ends of the propeller, although preferably it is applied after the fabric is relaxed on the belts traveling at the lower speed.

All parts of the fabric are supplied with steam at the same temperature and pressure, the treatment being uniform throughout the fabric as it advances. Owing to the relaxed condition of the fabric, the steam causes the stitches of the fabric to adjust themselves to their natural contour and form, and free of internal stress, and effects a reduction in the relaxation shrinkage, and shrinkage to the natural dimensions of the fabric results.

For many fabrics, an effective result is obtainable by applying steam to the lower portion of the fabric as it advances over the propeller belt mechanism, with or without a similar application of air to the upper portion of the advancing fabric.

Following the steaming and while the fabric is still relaxed, it may be subjected to a jet or jets of air, heated or cold, and applied to the top and bottom in opposed relation as in the case of steam, to avoid any distortion or tension in the fabric. In some cases, air is applied only to the bottom of the fabric. The amount of air and the temperature are such as to immediately remove the moisture present as the result of steaming.

The fabric may then pass without longitudinal tension into calender rolls for further finishing, if desired, provided that no longitudinal tension of the fabric is permitted. We have found, however, that calender rolls are not always necessary, since the treatment previously described delivers

some fabrics in a flat form and in suitable condition, free from wrinkles, so that it may be used for cutting. Where a pressing or ironing effect is desired on the fabric, the calender rolls are needed.

From the air jets and calender rolls, if used, the fabric, still without longitudinal tension but longitudinally compressed, is delivered to a conveyor consisting preferably of slats adapted to be advanced continuously by suitable driving means. The fabric loops itself between the slats and is conveyed without tension to the folder. Conveyor and folding mechanism, suitable for use with the present invention, is disclosed in the co-pending application Ser. No. 116,174 filed September 26, 1949, and the details thereof form no part of the present invention.

In the customary procedure for finishing or calendering tubular fabrics, spring pressure, usually light, is used on the finish rolls against the cloth to obtain a pressing or calendering effect. Such spring pressure exerted on the finish rolls is in addition to the normal weight of the finish rolls themselves. In the present apparatus, the weight of these rolls is approximately 150 pounds. It has been found that in order to get the best shrinkage results it is necessary to avoid finish roll pressure which tends to stretch the cloth.

While it is possible in some cases to separate or remove the finish rolls to obtain the best shrinkage results, in connection with many fabrics this presents a problem as it is important to obtain a pressing or calendering effect on the cloth in addition to the shrinkage thereof. Even though no spring pressure is used, the weight of the finish rolls themselves upon the cloth tends to stretch the cloth.

In order to avoid the pressure of the rolls against the fabric, but yet to have the fabric in contact with the rolls to obtain the pressing or calendering effect, a set of offset springs may be used to offset any or all of the weight of the finish rolls. With this offset pressure mechanism any pressure condition may be obtained from zero pressure at the finish roll nip up to more than the full weight of the rolls, or from zero pressure down to an actual opening of the finish rolls or as little pressure as is desirable in connection with the shrinkage result and cloth finish desired. Whenever the offset springs are in action, the upper roll begins to have its floating tendency. It is most desirable to have what we call a "featherweight pressure" which almost completely offsets the weight of the roll, but still results in a satisfactory pressing or calendering effect without affecting the processes of shrinkage initiated throughout the machine.

Referring to the drawing, 5 indicates the frame of the machine which is of suitable sturdy construction to withstand the stresses to which it is subjected. A pulley 6 (Fig. 2) is mounted on a shaft 7 extending transversely of the frame and is adapted to be driven from any suitable source of power such as an electric motor. The shaft 7 carries a variable speed pulley 8 from which other parts of the mechanism are driven in the manner hereinafter described. A sprocket 9 on the shaft 7 is connected by a chain 10 to a sprocket 11 on the stub shaft 12 which also carries a sprocket 13 connected by a chain 14 to a sprocket 15 on a shaft 16 extending across the frame and mounted in suitable bearings thereon.

The fabric 17 passes over roller 18, under roller 19, and over roller 20, all of which are mounted

on shafts extending transversely of the frame. These rollers serve merely as guides for the fabric. The fabric then passes onto the spreader or propeller as shown more clearly in Figs. 2 and 6 of the drawings.

The propeller consists of frames 21 connected to central members 22. The members 22 are joined by a rod 23, and rods of different lengths can be substituted to adjust the mechanism to the desired width of the fabric. The frames 21 carry rollers 24 and pulleys 25 and 26 disposed respectively at the central and end portions of the frame. Endless belts 27 are disposed about the pulleys 25 and 26 so that the belts are exposed to and engage the edges of the fabric which are advanced continuously in a flattened and laterally spread condition. The groove in pulley 25, at the left viewing Fig. 4, is of smaller diameter than the adjacent pulley 26, so that when driven in the manner hereinafter described, the belts 27 at the left of Fig. 4 travel at a lower speed than that of the belts 27 at the right of the figure. Consequently, as the fabric passes over the spreader, the forward portion thereof will be retarded with the result that the fabric forms ruffles 28 (Fig. 2) being thus relaxed longitudinally and consequently free from longitudinal tension. This is an essential feature of the invention, upon which the successful operation depends.

To drive the pulleys 25, the shaft 16 (Figs. 2, 5 and 6) carries worms 29 engaging worm gears 30 on shafts 31 vertically mounted in the frame. At the upper ends of the shafts 31, driving wheels 32 are provided with peripheral grooves 34 adapted to engage the fabric 17 at the edge thereof as indicated in Fig. 6. The fabric is thus held between the belts 27 and the pulleys and the surface of the driving wheel's 32. The surfaces of the belts 27 are relatively resilient, so that the fabric 32 is gripped positively and thus advances without friction or slipping. The positive feeding of the fabric assures the result indicated in Fig. 2. The grooves in the pulleys 25 and 26 are knurled or hobbed, as indicated at 35 (Fig. 8) and engage the soft surface of the belts 27 to ensure positive drive.

While the fabric is in the condition indicated at the left in Fig. 2, steam is applied thereto from steam chests 36 disposed above and below the fabric so that jets of steam are projected on the upper and lower sides thereof and directly opposed to each other and in balanced relation with respect to pressure, the purpose being to avoid any distortion of the fabric or the introduction of any longitudinal tension thereto during the steaming operation. The precise structure of the steam chests 36 is the subject matter of a co-pending application Serial No. 118,086 filed September 27, 1949, and forms no part of the present invention. As previously indicated, other types of steam chests may be used and the steam may be applied only to the under side of the fabric.

Following steaming of the fabric, it may be subjected to jets of air applied from pipes 37 disposed above and below the fabric or merely below the fabric and supplied with air under pressure, either heated or cold, through a trunk 38 from a suitable blower 39. As hereinbefore indicated, the air is not essential and may be omitted.

The fabric, still free from longitudinal tension, passes to the finishing rolls 40 and 41, if such rolls are employed. The rolls 40 and 41 are driven from a pulley 42 which is connected by 75

a belt 43 to the variable speed pulley 8, and thus the speed of the rolls can be controlled so as to avoid the application of longitudinal tension in the fabric passing between the rolls. In order to adjust the pressure applied by the rolls 40 and 41 as the fabric passes between them, the upper roll 40 is supported in bearings in pivoted arms 44, the ends of which embrace rods 45. Springs 46 and 47 are disposed above and below the arms 44, the upper spring 46 being adapted to force the roll 40 toward the roll 41, whereas the spring 47 has the opposite effect. The ends of the rods 45 are connected to cranks 48 on a shaft 49 extending transversely of the frame of the machine. An arm or lever 50 is also connected to the shaft 49 and may be shifted about a segment 51 which is suitably supported on the frame of the machine. By raising the arm 50, the springs 47 are caused to overcome the tension of the springs 46, and the lowering of the arm 50 permits the springs 46 to exert their pressure on the arm. Thus, depending upon the position of the arm 50, the full weight of the roll 40 plus the biasing effect of the springs 46 may be applied to the fabric, whereas if the arm 50 is raised, thus overcoming the tension of the springs 46, the weight of the roll 40 is overcome and the pressure may be zero or less. The preferable pressure applied between the rolls 40 and 41 is a so-called "featherweight" pressure, but any desired degree of pressure or none at all may be exerted upon the fabric by a simple adjustment of the arm 50. With "featherweight" pressure, the rolls 40 and 41 exert no tendency to effect longitudinal tension in the fabric which passes therethrough in relaxed condition, as is desirable to secure the preferred result.

A conveyor (Fig. 3) receives the fabric 17 and conveys it upwardly from the treating mechanism. The conveyor consists of a plurality of slats 52 mounted upon chains 53 which extend over sprockets 54 and 55. The sprocket 55 is driven by a belt 56 connected to the sprocket and a pulley 57 on a shaft 58 extending transversely of the frame of the machine. The pulley 57 is driven through a belt 59 from a pulley 60 which is, in turn, driven through a belt 61 from a pulley 62 on the shaft 63 extending transversely of the machine and carrying a pulley 64 driven by a belt 65 from the variable speed pulley 8. Thus, the fabric is conveyed upwardly without longitudinal tension and delivered to the folding mechanism, the details of which are described in application Ser. No. 116,174 filed September 16, 1949, and form no part of the invention except for an improvement hereinafter described. The mechanism of the prior application includes swinging arms 66 actuated in the manner described in said application and carrying rollers 67 at their lower ends which feed the fabric to a table 68 which mechanism above the table is adjustable as the pile of fabric increases.

The improvement of the present application relates to means for automatically threading the fabric through the rollers 67 when a fresh end of the fabric is delivered. It consists of a plate 69 pivotally connected to the lower ends of the arms 66 and slidable between pins 70 on a bracket 71. On the opposite side, plate 72 telescopes within a plate 73. The plate 72 is pivoted at the lower end of the arms 66, and the plate 73 is pivoted at 74 on a bracket 75. Thus, as the arms 66 swing backwardly and forwardly to distribute the fabric upon the table 68, the plates 69, 72 and 73 swing with it. When a fresh end of the fabric

is introduced by the conveyor, it falls between the plates 69 and the plates 72 and 73, and the end is readily gripped between the rollers 67 without any manual operation. The details of the operation of the arms 66 need not be described in detail, because it is fully described in the co-pending application. This improvement in the folding mechanism is described and claimed in our copending application Ser. No. 257,087, filed November 10, 1951.

The invention as set forth depends upon the treatment of the fabric, while it is relaxed and entirely free from longitudinal tension, with an aqueous medium such as steam or atomized water. This condition is achieved in the novel manner described through the use of a propeller by which the fabric is advanced at predetermined differential speeds in two successive zones, the forward zone being propelled at a lower speed so that the fabric forms ripples. The edges of the fabric are propelled positively and without friction, and hence longitudinal tension is completely relieved.

In the relaxed condition, the fabric is steamed. The steam is applied to the upper and lower surfaces of the fabric in a manner such that all pressure is balanced, or only to the lower surface, and the fabric is not subjected to any tension during steaming. Thereafter, the moisture may be removed by air jets similarly applied to avoid distortion due to the pressure of the jets. Air drying may, however, be omitted.

Whether or not air is used for drying, the fabric may be subjected to rolling pressure applied so as to avoid longitudinal tension. The pressure is preferably adjusted to a "feather-weight" pressure in which the rolls just contact the opposite sides of the fabric without applying any substantial pressure thereto. However, the pressure may be adjusted as required. The "featherweight" pressure has been found sufficient to remove irregularities of the surface of the fabric and to give a desired finished appearance. In many cases the rolling pressure may be omitted. The fabric, directly after steaming, may be delivered to the conveyor and carried thereby to the folding mechanism. Usually the passage of the material over the conveyor allows sufficient time for drying of surplus moisture.

By "transversely rifled" is meant that wrinkles, creases, folds or ripples are formed in the fabric each extending transversely across the fabric. It will also be clear from the above that by "steaming" or "applying steam" we mean to include the application to the fabric of any aqueous medium such as steam or water as a finely divided spray.

Various changes may be made in the details of the apparatus and in the operation thereof without departing from the invention or sacrificing the advantages thereof.

We claim:

1. The method of treating tubular textile fabric which comprises spreading the fabric to flattened form and advancing rearward and forward portions at differential speeds so that the forward portion is relaxed and completely free from longitudinal tension, and applying steam simultaneously to the upper and lower sides of the relaxed and advancing fabric.
2. The method of treating tubular textile fabric which comprises spreading the fabric to flattened form and advancing rearward and forward portions at differential speeds so that the forward portion is relaxed and completely free from longitudinal tension, applying steam to the relaxed and advancing fabric, and conveying the fabric in a relaxed condition.

tudinal tension, applying steam simultaneously to the upper and lower sides of the relaxed and advancing fabric, and subjecting the fabric to rolling pressure while it is still relaxed and free from longitudinal tension.

3. The method of treating tubular textile fabric which comprises spreading the fabric to flattened form and advancing rearward and forward portions at differential speeds so that the forward portion is relaxed and completely free from longitudinal tension, and applying steam to the relaxed and advancing fabric.

4. The method of treating tubular textile fabric which comprises spreading the fabric to flattened form and advancing rearward and forward portions at differential speeds so that the forward portion is relaxed and completely free from longitudinal tension, applying steam simultaneously to the upper and lower sides of the relaxed and advancing fabric, and conveying the fabric in a relaxed condition.

5. The method of treating tubular textile fabric which comprises spreading the fabric to flattened form and advancing rearward and forward portions at differential speeds so that the forward portion is relaxed and transversely rifled and completely free from longitudinal tension, applying steam simultaneously to the upper and lower sides of the relaxed and advancing fabric, and subjecting the fabric to rolling pressure while it is still relaxed and free from longitudinal tension.

6. The method of treating tubular textile fabric which comprises spreading the fabric to flattened form and advancing rearward and forward portions at differential speeds so that the forward portion is relaxed and transversely rifled and completely free from longitudinal tension, and applying steam simultaneously to the upper and lower sides of the relaxed and advancing fabric.

7. The method of treating tubular textile fabric which comprises spreading the fabric to flattened form and advancing rearward and forward portions at differential speeds so that the forward portion is relaxed and completely free from longitudinal tension, applying steam to the advancing fabric, and subjecting the fabric to rolling pressure while it is still relaxed and free from longitudinal tension.

8. The method of treating tubular textile fabric which comprises spreading the fabric to flattened form and advancing rearward and forward portions at differential speeds so that the forward portion is relaxed and completely free from longitudinal tension, applying steam to the relaxed and advancing fabric, and conveying the fabric in a relaxed condition.

9. The method of treating tubular textile fabric which comprises spreading the fabric to flattened form, advancing the fabric so that the forward portion is relaxed and completely free from longitudinal tension, and applying steam to the relaxed portion of the advancing fabric.

10. The method of treating tubular textile fabric which comprises spreading the fabric to flattened form, advancing the fabric so that the forward portion is relaxed and completely free from longitudinal tension, applying steam to the advancing fabric, and subjecting the fabric to rolling pressure while it is still relaxed and free from longitudinal tension.

11. The method of treating tubular textile fabric which comprises spreading the fabric to flattened form, advancing the fabric so that the forward portion is relaxed and completely free from longitudinal tension, applying steam to the ad-

vancing fabric, and subjecting the fabric to rolling pressure while it is still relaxed and free from longitudinal tension, and adjusting the pressure applied to the fabric to avoid the application of longitudinal tension thereto.

12. The method of treating tubular textile fabric which comprises spreading the fabric to flattened form, advancing the fabric so that a portion thereof is relaxed and completely free from longitudinal tension, simultaneously applying steam to both sides of the relaxed portion of the fabric, and conveying the fabric in a relaxed condition.

13. The method of treating tubular textile fabric which comprises spreading the fabric to flattened form, advancing the fabric so that a portion thereof is relaxed and completely free from longitudinal tension, applying steam to the relaxed and advancing fabric, and subjecting the fabric to rolling pressure while it is still relaxed and free from longitudinal tension.

14. The method of treating tubular textile fabric which comprises spreading the fabric to flattened form, advancing the fabric so that a portion thereof is relaxed and completely free from longitudinal tension, applying steam to the relaxed portion of the fabric, and conveying the fabric in a relaxed condition.

15. The method of treating tubular textile fabric which comprises spreading the fabric to flattened form, advancing the fabric so that a portion thereof is relaxed and transversely rifled and completely free from longitudinal tension, and applying steam to the advancing fabric.

16. The method of treating tubular textile fabric which comprises spreading the fabric to flattened form, advancing the fabric so that a portion thereof is relaxed and transversely rifled and completely free from longitudinal tension, and simultaneously directing steam upon opposite sides of the advancing fabric.

17. In an apparatus for treating tubular textile fabric, means for advancing portions of the fabric in flattened form at differential speeds whereby the forward portion of the fabric is relaxed and completely free from longitudinal tension, means for applying steam to the advancing fabric, means for applying rolling pressure to the relaxed fabric, and means for adjusting the pressure applied by the rolling pressure means, including a roll, bearings supporting the roll, resilient means effective on opposite sides of the bearings, and means for adjusting the position of the bearings.

18. In a propeller for treating tubular textile fabrics, a frame adapted to be inserted within the fabric, endless belts supported on the frame at the sides thereof, and common driving means for driving the belts at one end of the frame at a linear speed exceeding that of the belts at the opposite end.

19. A propeller for treating tubular textile fabric comprising a frame, two sets of endless belts, pulleys supporting the belts at the edges of the frame, and common driving means for the pulleys, the pulleys for the two sets of belts being proportioned relatively so that one set of belts travels at a linear speed lower than that of the other set of belts.

20. In an apparatus for treating tubular textile fabric, a propeller consisting of side members and connecting means between them, each side member comprising a frame, a pair of pulleys at the intermediate portion of the frame, pulleys at the ends of the frame and belts connecting the pulleys

at the ends of the frame respectively with one of the pair of pulleys at the intermediate portion of the frame, one of the pair of pulleys at the intermediate portion of the frame being smaller in effective diameter than the other, whereby the respective belts travel at different speeds.

21. In an apparatus for treating tubular textile fabric, a propeller consisting of side members and connecting means between them, each

10 side member comprising a frame, a pair of pulleys at the intermediate portion of the frame, pulleys at the ends of the frame, both pairs of pulleys having belt receiving grooves, and belts connecting the pulleys at the ends of the frame

15 respectively with one of the pair of pulleys at the intermediate portion of the frame, the grooves in one of the pair of pulleys at the intermediate portion of the frame being deeper than the grooves in the other.

20 22. In an apparatus for treating tubular textile fabric, means for advancing the fabric, rolls for applying rolling pressure to the fabric, and means for adjusting the rolling pressure between less and more than the weight of the upper roll, including bearings for the upper roll, springs above and below the bearings, and lever means for adjusting the bearings relatively to the springs.

23. The method of treating tubular textile fabric which comprises spreading the fabric to flattened form, advancing the fabric so that a portion thereof is relaxed and transversely rifled and completely free from longitudinal tension, applying steam to the fabric, and conveying the fabric in relaxed condition.

30 24. The method of treating tubular textile fabric which comprises spreading the fabric to flattened form and advancing rearward and forward portions at differential speeds so that the forward portion is relaxed and transversely rifled and completely free from longitudinal tension, applying steam to the relaxed and advancing fabric, and conveying the fabric in relaxed condition.

35 25. The method of treating tubular textile fabric which comprises spreading the fabric to flattened form, advancing the rearward and forward portions at differential speeds so that the forward portion is relaxed and completely free from longitudinal tension, applying steam to the advancing fabric, subjecting the fabric to rolling pressure while it is still relaxed and free from longitudinal tension, and conveying the fabric in relaxed condition.

40 26. The method of treating tubular textile fabric as set forth in claim 25 in which the forward portion of the fabric is transversely rifled

45 27. In an apparatus for treating tubular textile fabric, propeller means for advancing the fabric in flattened form including a frame adapted to be inserted within the fabric and endless belts supported on the frame at the sides thereof and common driving means for driving the belts at one end of the frame at a speed different from those at the opposite end whereby the forward portion of the fabric is relaxed and completely free from longitudinal tension, and means for applying steam to the fabric.

50 28. An apparatus according to claim 27 which includes means for applying steam to both sides of the fabric and means for applying roller pressure to the relaxed fabric.

55 29. An apparatus according to claim 28 including means for conveying the fabric in relaxed condition.

60 30. Apparatus for treating traveling tubular

11

textile fabric comprising means for advancing the fabric in flattened form, means for transversely riffling the fabric, finishing rolls for pressing the fabric, means for steaming the fabric and means for maintaining the fabric in a rifled and relaxed condition free of longitudinal tension during the steaming.
